UNITED STATES PATENT OFFICE.

JAMES A. SMITH, OF WASHINGTON, DISTRICT OF COLUMBIA, ASSIGNOR OF ONE-HALF
TO WILLIAM N. DORSETT, OF WASHINGTON, DISTRICT OF COLUMBIA.

COMBINED ARCH AND SHOE-STRAIGHTENER.

1,191,543.

Specification of Letters Patent. Patented July 18, 1916.

Application filed July 2, 1915. Serial No. 37,791.

To all whom it may concern:

Be it known that I, JAMES A. SMITH, a citizen of the United States, residing at Washington, in the District of Columbia, 5 have invented certain new and useful Improvements in Combined Arches and Shoe-Straighteners; and I do declare the following to be a full, clear, and exact description of the invention, such as will enable others skilled in the art to which it appertains to 10 make and use the same.

This invention relates to improvements in arch supports and more particularly to what may be termed arch cushions and which are 15 worn outside a shoe on the shank of the sole thereof.

The main object of the invention is to provide a combined arch cushion and shoe straightener so constructed as to be shiftable 20 to properly position it where needed most, according to the manner in which the shoe to which it is applied is worn, as some persons walk on one side of the foot and some on the other and by the use of this device, 25 this tendency may be overcome.

Another object is to provide a combined reinforce and attaching device for securing the cushion to the shoe.

Another object of the invention is to provide 30 a cushion of this type constructed of resilient material such as rubber and designed to be attached outside of a shoe to the shank of the sole thereof adjacent the breast of the heel.

In the accompanying drawings: Figure 1 35 represents a side elevation of a shoe equipped with this improved cushion with parts broken out; Fig. 2 is a bottom plan view thereof with the cushion shown in dotted 40 lines arranged for straightening a shoe; Fig. 3 is a perspective view of the attachment detached; Fig. 4 is a longitudinal section through the cushion showing one form of reinforce; Fig. 5 is a plan view of the reinforce shown in Fig. 4; Fig. 6 is a transverse section taken on the line 6—6 of Fig. 5; Fig. 7 is a perspective view showing another 45 form of reinforce applied; Fig. 8 is a similar view of the reinforce detached; Fig. 9 is a perspective view of the cushion and reinforce employed in Figs. 1 to 3; Fig. 10 is a similar view of the reinforce; Fig. 11 is a perspective view of another form of reinforce; Fig. 12 is a perspective view of a 50 cushion with this reinforce embedded; and Fig. 13 is a perspective view of the end securing tack.

Fig. 13 is a perspective view of the end securing tack.

In the embodiment illustrated in Figs. 1 to 3, a rubber heel 1 is shown having secured to its inner face at the breast thereof, a 60 cushion 2 constituting the invention and which in this form is made integral with the heel. This cushion 2 is constructed of a solid elongated block of rubber sufficiently 65 resilient to yield slightly on the exertion of considerable pressure thereon and yet sufficiently solid to support the arch of the wearer against collapse. This cushion 2 is made in the form of a wedge-shaped block 70 about three-fourths of an inch wide more or less and of a length corresponding to the distance between the breast of a shoe heel and the front end of the shank of the sole of the shoe, which is ample to provide a proper arch support and yet render the device 75 light enough not to noticeably increase the weight of the shoe to which it is attached. This cushion is flat and straight throughout its lower surface engaging face as shown at 3 while its sole engaging face 4 80 is inclined downwardly from its rear to its front end, the incline from midway its length to its rear end being very slight while from 85 said intermediate point to its front end the inclination is abrupt to produce a thin tapered front end 5 which when applied merges gradually into the sole of the shoe at the front end of the shank adjacent the ball of the foot. This wedge-like cushion is 90 sufficiently resilient to adapt the front portion thereof to be moved laterally to one side or the other according to the tendency of the wearer to run down his shoe at one side or the other, this lateral shifting of the cushion 95 serving to correct this tendency and retain the shape of the shoe.

To prolong the life of the cushion, to facilitate its attachment and retention in operative position, and provide for its lateral bending at the thicker heel breast engaging 100 end, the reinforce 6 is provided which may vary somewhat in construction or rather in the means for securing it to the shoe heel, the structure of the body being the same in all the forms, several of which are shown in the different figures. These reinforces 6 are each constructed of a strip of sheet metal, thin and light, aluminum being preferably used although not necessarily. These strips all have a twist 7 formed adjacent their rear 110

end. The twist is sufficient to position their front and rear ends in the same plane and yet facilitate the lateral yieldability of the strip toward one side or the other of the block 2, to provide for the lateral movement of the front portion of the cushion in which said reinforce is embedded.

In the form shown in Figs. 1 to 3 the cushion 2 is made integral with the heel 1 and the reinforce 6 shown in Figs. 9 and 10 is embedded in the cushion 2 thereof with the apertured front end 7 thereof positioned in the thin front end of the cushion 2, the aperture in said end 7 registering with the aperture 8 in said cushion to receive the fastening element for securing it to the shoe sole. A tack 9 is here shown for securing the front end of the cushion and comprises a shank 10 having a penetrating point 11 at one end and a cap-like head 12 at the other, said head being here shown shaped to fit the thin front end of the cushion 2, being provided at its front and on two sides with depending flanges 13 and 14 respectively which engage the tip and sides of the cushion and serve both as a securing element and as a protector for the front end or tip of the cushion.

The reinforce 6 has a twist 6' near its rear end to provide a determinate flexing point or 30 flexible connection between its front and rear portions to permit the front portion in advance of said twist to swing freely from one side to the other without danger of breakage, the upright portion 6'' formed by said twist 6' forming a hinge-like connection which could not be obtained otherwise, the edgewise positioning of the remainder of the reinforce in the cushion affording the desired stiffening or reinforcing effect. The rear end 7' 40 of the reinforce 6 is also apertured and is designed to enter the breast of the heel and be secured by the central fastening element 1' which assists in connecting the rubber heel 1 to the leather heel H. Hence it will be seen that by embedding the strip having a determinate flexing point intermediate of its ends in the cushion and extending one end thereof into the heel and there securing it the front portion of the cushion may be shifted laterally toward one side edge or the other of the shoe sole without danger of the cushion being torn or separated from the heel. Thus the retention of the heel and cushion in unitary form will be insured while permitting the 50 front portion of the cushion to be moved to one side edge or the other of the shoe sole. In this form the combined rubber heel and cushion are sold as a unitary structure and so applied to a shoe.

60 In Figs. 4, 8 and 12 the cushion is shown as separate from the heel.

In Figs. 4 to 6, a combined reinforce and cushion connector 15 is shown composed of a strip of thin sheet metal folded longitudinally and of uniform width throughout the

greater portion of its length, being made wider at one end as shown at 16 and with the end of said wider portion extended beyond the thicker end of the cushion 2 and slit at the folded portion thereof to form attaching arms 17 and 18 which are extended laterally in opposite directions and apertured for the passage of fastening elements for connecting the cushion to the breast of a shoe heel. The opposite end of said reinforce has one thickness thereof cut away and provided with an eye 19 for receiving the fastening element which connects the front end of the cushion to the shoe sole. This strip 15 is twisted adjacent the wider portion thereof to position said wider portion vertically in the cushion to provide for the lateral yielding of said cushion 2 to adapt it to be so bent that the ends thereof may be arranged at different positions on the shoe to prevent it from being run over on one side or the other.

Figs. 7 and 8 show a single strip 20 similar to strip 6 except that it is provided at its rear end with a cross bar 21 having rearwardly extending prongs 22 at its ends for penetrating a heel breast for connecting the thicker rear end of the cushion to said heel.

Figs. 11 and 12 show a reinforcing strip 20' similar to strip 6 except that it has a single heel penetrating prong 21' extending 95 longitudinally from its rear end.

This combined reinforcing and attaching strip of the various figures retains the cushion in shape at all times, and thus greatly increases the comfort of the wearer while 100 prolonging the life of the cushion.

I claim as my invention:

1. A shoe shank arch cushion comprising a resilient block adapted to fit the outer surface of a shoe shank, and a reinforcing and connecting strip embedded in said resilient block and having a projecting end for engaging a shoe heel, said strip having a determinate flexing point between the ends of said block whereby its front end may be 105 adjusted toward either edge of the shoe sole.

2. A shoe shank arch cushion comprising a resilient block thicker at one end than at the other, and a thin metal strip arranged therein with its edges extending toward the sides of the block, and a twist formed in said metal strip intermediate of its ends to permit the cushion to yield laterally toward either edge of the shoe sole 120 to which it is applied to provide for varying the position of the front portion of said block to dispose it nearer to one side or the other of the shoe sole.

3. A shoe shank arch cushion comprising 125 a solid rubber block tapering in thickness toward one end, a reinforcing strip of sheet metal extending longitudinally throughout the length of said rubber block, with its edges extending toward the sides of the 130

block, and having a twist formed therein at the thicker end of said rubber block to present a vertically disposed flat member with its edges extending toward the top and bottom of said rubber block to provide for the lateral bending of said block intermediately of its ends, whereby its front end may be adjusted toward either edge of the shoe sole.

4. A shoe shank arch cushion comprising a resilient block thicker at one end than at the other and a reinforce embedded in said block and having a heel engaging element extending longitudinally through the thicker end thereof, said reinforce having a flexible connection between its ends whereby the thinner end of said block may be adjusted toward either side edge of the shoe sole.

5. A shoe shank-arch cushion comprising a resilient block thicker at one end than at the other, and a reinforce embedded in said block, and having a cross bar projecting beyond the thicker end thereof and provided with means for connecting it to the breast of a heel, said reinforce having a flexible connection intermediately of its ends to adapt the cushion to yield laterally relative to the side edges of the shoe sole to which the cushion is applied.

6. A shoe shank arch cushion comprising a resilient block thicker at one end than at the other and a laterally yieldable reinforce embedded in said block and having a heel engaging element extending longitudinally through the thicker end thereof, and its other end apertured and positioned in the

thinner end of said block, a fastening element having a shank for insertion through said thinner block end and the aperture in said reinforcing strip, and a cap on said shank having flanges for engaging the sides and front end of said block.

7. A shoe shank arch cushion comprising a solid rubber elongated block thicker at one end than at the other and having a rectilinear surface engaging face and a curved shoe engaging face, and a combined reinforce and connecting member embedded in said block and having a twist formed therein intermediately of its ends.

8. A rubber heel having a resilient block extending from the breast thereof and made integral therewith to form an arch cushion, and a reinforcing strip embedded in said block and extending the full length thereof with one end projecting into said heel, said strip having a determinate flexing point between the ends of said block to provide for the shifting of the front end of said block toward either edge of the shoe sole, the extension of the strip into the heel serving to prevent the cushion from being torn from the heel when the position of the cushion is shifted.

In testimony whereof I have hereunto set my hand in presence of two subscribing witnesses.

JAMES A. SMITH.
